United States Patent

Des. 239,321
Patented Mar. 23, 1976

239,321

PORABLE RADIO

Paul J. Klucznik, Manlius, N.Y., assignor to
General Electric Company, Syracuse, N.Y.

Filed Jan. 7, 1974, Ser. No. 431,378

Term of patent 14 years

Int. Cl. D14—03

U.S. Cl. D56—4 B

FIG.1

FIG.2

FIG.3

FIG.4

FIG.5

FIG.6

FIG. 1 is a front elevational view of a portable radio showing my new design;

FIG. 2 is a top plan view with the handle in lowered position;

FIG. 3 is a right side elevational view thereof;

FIG. 4 is a left side elevational view thereof;

FIG. 5 is a rear elevational view thereof; and

FIG. 6 is a bottom plan view.

I claim:

The ornamental design for a portable radio, substantially as shown and described.
